UNITED STATES PATENT OFFICE.

HAMILTON NEIL WYLIE, OF LONDON, ENGLAND.

STRUCTURAL FRAMEWORK OF SHEDS, BRIDGES, AND THE LIKE.

Application filed October 31, 1924. Serial No. 747,017.

To all whom it may concern:

Be it known that HAMILTON NEIL WYLIE, a British subject, residing at Central House, Kingsway, London, W. C. 2, England, has 5 invented certain new and useful Improvements in Structural Framework of Sheds, Bridges, and the like, of which the following is a specification.

This invention relates to structural frameworks, often referred to as "bents", in which a horizontally disposed structure such as a roof truss, platform bridge or the like is supported upon uprights or stanchions.

The object of the invention is to provide 15 an improved means for erecting and taking down such structures particularly when of a temporary or portable nature.

In erecting the bent in accordance with the invention the girder is connected to the 20 ends of the stanchions, which will ultimately be in the upper position and which will be referred to as the upper ends, the lower ends being pivoted to fixed bases, and one of the stanchions is then extended. The 25 upper end is then constrained to move in a circular arc the centre of which is the other end of the girder and when raised to its fullest extent is guyed whereupon the other stanchion is extended and the girder 30 rises with it.

The invention is particularly applicable to metal framework for portable aircraft sheds which must be light and composed of short members for transport and must be 35 capable of being easily erected, preferably with the canvas or other covering for the roof in position.

In accordance with this invention the stanchions comprise two levers the fulcrum 40 of each of which is pivoted to a rigid link one arm of each lever being connected by a member of variable length, the arrangement being such that by shortening this member of variable length the ends of the other 45 arms may be moved from a position in which they are relatively near to an extended position in which these latter arms make with the rigid member an angle approaching 180 degrees.

50 In the accompanying drawings which illustrate a preferred embodiment of the invention,

Fig. 1 represents a view of the bent in the process of erection.

55 Fig. 2 represents a stanchion in its bent position prior to extension.

Fig. 3 represents a stanchion partly extended.

Fig. 4 represents in detail the lower portion of a stanchion in fully extended position.

Referring first to Figs. 2 and 3, each stanchion comprises two levers B, C pivoted at points a, b to a rigid link A; extensions B¹, C¹ of these levers are connected by 65 a cable F which passes over pulleys f¹, f² and can be varied in length by means of a drum G operated by a handle g. Bracing members B², B³, B⁴, B⁵, B⁶, and C², C³, C⁴ are provided to give increased strength to 70 the levers.

The end of the lever B is pivoted to a foundation base E and in the position shown in Fig. 2 the end c of the lever C is close to the base E; this end c is hinged to one 75 end of the girder H, which in the form shown is a roof truss and is shown in Fig. 1 in full lines with one end raised. If now the cable F be shortened, the levers will turn about the pivots a, b and as the end c 80 is constrained to move in a circular arc of radius equal to the span of the girder H, the latter being initially on the ground, both levers will rise, as shown in Fig. 3 and will ultimately come to the position shown in 85 Fig. 1 where the ends x, y of the levers come together.

These ends are then secured in position by a locking member J, Fig. 4. It will be noted in Fig. 1 that when the stanchion is 90 in its fully extended position the members B, A and C are not collinear; this ensures that the locking member will always be in tension and thus make it possible to detail 95 this member as a flexible one.

With the arrangement of levers shown in Figs. 2 and 3 the tension in the member F and therefore the force which has to be applied to the drum in winding will remain nearly constant as the stanchion moves from one extreme position to another. That is to say, the arm B' causes the perpendicular distance between the cable F and member A to vary in approximately the same degree as the perpendicular distance between 100 the member A and the weighted end c varies as extension takes place. Thus it may be said that the maximum tension is very little 105 in excess of the average tension throughout the operation.

110 In erecting the bent in accordance with this invention the stanchion at each end is

brought to the position shown in Fig. 2 and the girder or roof truss H is then pivoted at each end to the ends C. One stanchion is then extended and the girder at this end then moves in a circular arc about the other end as centre; when this stanchion is fully extended the parts assume the position shown in full lines in Fig. 1. A guy rope K is then put in position at the end C and the other stanchion is then extended thus bringing the parts to the position shown in dotted lines in Fig. 1. The position of the parts in the extreme position are shown in Fig. 4. When this position is reached, the locking member j is secured to both parts, the auxiliary rig arm (B') can then be removed; in practice it is removed when one side of the structure has been erected and is moved over onto the other side and then remains there for use in dismantling the second side first. The guys are then adjusted to bring the erected structure to final or symmetrical position.

The invention is applicable to cases in which one of the uprights or stanchions of the bent is an existing structure to the top of which access can be obtained. For example the structure may be erected upon one existing wall; one end of the girder is then first lifted to the top of the wall and the other end is raised by the aid of a stanchion operating in the manner previously described.

In a modification the rigid link A may comprise a triangulated or otherwise formed frame structure; and in all forms the shortening member F may be formed in two separate elements each separately connecting one of the levers to the rigid link and capable of separate adjustment.

I claim:-

1. A stanchion adapted to be used in a framed structure comprising a rigid link, two levers pivoted to said link at points intermediate their ends, and a member connected to one arm of each of said levers, said member being of adjustable length so that on being shortened the free arms of said levers move apart and increase the effective length of the stanchion, and the first-named arms come into contact with one another to form a triangle with the link as its base.

2. A stanchion adapted to be used in a framed structure comprising a rigid link, a lever pivoted at one end of said link, a lever pivoted at the other end of said link, a member of variable length connecting an arm of one of said levers to an arm of the other of said levers, the free ends of said levers moving from proximity to one another (when said member is lengthened) a distance apart approximately representing the sum of the lengths of said free arms and said link (when said member is shortened).

3. A stanchion adapted to be used in a

framed structure consisting of a rigid link, two triangulated members each pivoted to said link at a compound angle, means to hinge one triangulated member to a base at a second angle, and a second angle of the other triangulated member being constrained to move in a predetermined path, flexible means of adjustable length being connected to the remaining apices of the members whereby the stanchion may be brought from a position in which the second apices are in proximity to one in which they are practically collinear with the rigid link and to any intermediate position at will.

4. A stanchion adapted to be used in a framed structure comprising a rigid link, two levers pivoted to said link at points intermediate their ends, and a member connected to one arm of each of said levers, said member being of adjustable length so that on being shortened, the free arms of said levers move apart and increase the effective length of the stanchion, the first-named arms coming into contact with one another at some little distance from said link, and locking means to retain said contact.

5. A stanchion adapted to be used in a framed structure comprising a rigid link, two levers pivoted to said link at points intermediate their ends, and a member connected to one arm of each of said levers, said member being of adjustable length so that on being shortened the free arms of said levers move apart and increase the effective length of the stanchion, the first-named arm of one of said levers having a greater effective length than that of the first-named arm of the other of said levers for the purpose of varying the inclination of said member to said link in such a way as to maintain the tension in said member substantially constant through the greater portion of the movement of the levers.

6. A stanchion adapted to be used in a framed structure comprising a base, a rigid link, two levers pivoted respectively at the two ends of said link, one arm of one of said levers being pivoted to said base and one arm of the other of said levers being adapted to support a load, and flexible means to draw towards one another the other arms of said levers for the purpose of separating the said first-mentioned arms in order to raise the load.

7. A bent comprising a girder, a base under each end of said girder, a pair of extensible stanchions one pivoted at each end of said girder and to the corresponding base, means to extend one stanchion while said girder swings about the upper end of the other in its unextended position, and means to extend the second stanchion while said girder swings about the upper end of said first-named stanchion.

8. A bent comprising a girder pivoted at

each end to one of a pair of stanchions, each stanchion comprising two arms each pivoted to a rigid connecting link and each having an extension beyond said link, and 5 flexible means connected to said extensions and operable to vary the relative positions of said arms and link from a position in which they form substantially a triangle to a position in which they form substantially 10 a straight line.

9. A stanchion comprising a base, an arm adapted to be pivoted to said base, a link pivoted to said arm, a second arm pivoted to said link and adapted to carry a load, an 15 extension to each of said arms, flexible

means of variable length so connected to said parts that when extended sufficiently said arms and said link form substantially a triangle and when shortened sufficiently 20 substantially a straight line, said extensions and said link in the shortened position forming a triangle and means to lock the extensions in the last-named position.

10. A bent comprising the parts and arrangement set out in claim 7 together with guys attached adjacent the upper ends of 25 said stanchions.

In testimony whereof I affix my signature.

HAMILTON N. WYLIE.
